UNITED STATES PATENT OFFICE.

JOHN PHILO COWING, OF CLEVELAND, OHIO.

AUTOMATIC DERAILER FOR DRAWBRIDGES.

SPECIFICATION forming part of Letters Patent No. 738,297, dated September 8, 1903.

Application filed August 27, 1901. Serial No. 73,430. (No model.)

To all whom it may concern:

Be it known that I, JOHN PHILO COWING, of Cleveland, in the county of Cuyahoga and State of Ohio, have invented a new and useful Improvement in Automatic Derailers for Drawbridges, of which the following is a full, clear, and exact description.

The object of the invention is to provide a new and improved gate with derailler and signal device more especially designed for use on draw or swing bridges on lines of railroads and arranged so that immediately previous to opening the draw or swing the gates are automatically closed, the derailler is set to run the traffic off to one side of the track, and a signal set to show that the bridge is open, and immediately after closing the draw or swing the gates are automatically opened, the derailler set for clear traffic, and the signal shown that the bridge is ready for traffic.

The invention consists of novel features and parts and combinations of the same, as will be fully described hereinafter and then pointed out in the claims.

25 A practical embodiment of my invention is represented in the accompanying drawings, forming a part of this specification, in which similar characters of reference indicate corresponding parts in all the views.

30 Figure 1 shows a general arrangement of the gates, derailler, and signal device in plan. Fig. 2 shows an elevation of the gates when closed. Fig. 3 shows the gates open and the end of the draw with operating mechanism for the gates. Fig. 4 shows a top view of the operating mechanism for the gates. Fig. 5 shows an elevation of the operating mechanism for the derailler. Fig. 6 shows a top view of the operating mechanism for the derailler. 35 Fig. 7 shows the lower end of the signal-pole with operating mechanism. Fig. 8 shows a top view of the lower end of the signal-pole with operating device. Fig. 9 shows a transverse sectional view of the derailler. Fig. 10 shows a top view of the derailler. Fig. 11 shows a longitudinal section of the derailler. Fig. 12 shows a top view of the signal-pole with semaphore-signal.

40 The gates illustrated in Figs. 1 and 2 and marked A and A' are arranged so that the roadway-section A extends over the whole or half of the roadway B to close the same and

a sidewalk-section A' arranged to extend over the sidewalk C, a weight A² being provided for counterbalancing the longer roadway-section 55 A. The gate A is provided with the shaft D, which is pivotally mounted in bearings E and F. The said shaft D is provided at its lower end with a lever L³, Figs. 2, 3, and 4, which connects to the rod L', which when moved causes 60 the shaft to revolve about its vertical axis, thereby causing the gate to move into an open or closed position. The sidewalk-gate A' is provided with a shaft D', Fig. 2, which is pivotally mounted on bearings E' and E². 65 The shaft D' is provided with a gear G at its upper end, which is in mesh with a similar gear G at the upper end of the shaft D, so that when the shaft D is revolved a rotary motion is also transmitted through the gears 70 G to the shaft D', which is rigidly fastened to the gate A', and thereby causes the gates A and A' to open simultaneously toward the center of the draw or in the direction in which the traffic is going on the draw after swinging 75 into a closed position. It is plainly evident that the gates A and A' may be mounted on the shaft D and that one gate may swing toward the center of the draw and the other away from the center of the draw, but I have 80 shown them in this case as both swinging toward the center of the draw or swing bridge.

The rod R', Figs. 3 and 4, is extended beyond the lever L³ to receive the rod R², which is connected to the lever L⁴, Figs. 5 and 6, 85 the lever L⁴ being rigidly fastened to the shaft D³. This shaft D³ has rigidly fastened at its upper end the lever L⁵, which is connected to the rod R⁴. The said rod R⁴ is extended to connect to a lever, Fig. 12, which is part of 90 the switch-point, and when the rod R⁴ is moved the rod R², shaft D³, levers L⁴ and L⁵, and rod R⁴, all of which cause the switch-point to open or close according to as the rods are moved. The switch-point is pivotally mounted on a 95 shaft in a casing forming part of the track for the tread of the wheel to run on, and the switch-point is arranged to deflect the wheels on the main track or off to one side. The said switch-point is provided with lugs to prevent anything from falling into the switch-casing. The casing is also provided with a drainage-hole to take away the water that may run down the track. The casing has a 100

hole in one side to receive the rod R^4 , which is operated in a conduit, the said conduit connecting to a hole in the side of said casing, which will permit the rod to have an obstructed movement between the lever on the switch-point and the lever L^5 at the top of the shaft D^3 , Figs. 5 and 6. The rod R^2 is extended beyond the lever L^4 to receive the rod R^3 , Fig. 7, which is extended to connect to the lever L^6 , which lever is rigidly fastened to the shaft D^4 , Fig. 8, which is pivotally mounted to turn in the bearing B' and has the lever L^7 rigidly fastened to the end, the lever L^7 being arranged to extend inside of the pole, which is erected a suitable distance from the gates and has one fixed arm and one movable arm which act as signals to show when the bridge is open or closed. The pole is arranged to have the rod R^5 pass through the center of the pole and to connect to the movable arm R^6 , Fig. 12. The rod may be arranged to pass to the movable arm on the outside of the pole, but for appearance have shown it inside of the said pole. The said lever L^7 connects to the rod R^5 , Fig. 7. The said rod R^5 connects to the movable arm R^6 at the top of the signal-pole P , Fig. 12. When the said rod R^3 moves, the levers L^6 and L^7 , and the rod R^5 , and movable arm R^6 of the signal-pole moves up or down and thereby causes a signal to be given by displaying color of light to indicate the position of the bridge at night. The fixed arm w^t at the top of the signal-pole is provided with a light which shows the signal at night, and during the day the position of the movable arm shows the position of the bridge. The end of the said draw or swing span (shown in Fig. 3) is provided with a movable base H , which is moved up and down by the drawbridge mechanism and engages the lever L^2 , which is rigidly fastened to the shaft I , said shaft I being pivotally mounted to turn in bearings J and having the lever L' rigidly fastened. When the lever L^2 moves, the lever L' also moves, and by this movement the gates, derailer, and signal are operated simultaneously.

When the bridge is closed and the movable base H is down, the gates are forced open, the derailer is for clear track, and the signal displayed shows that the bridge is ready for traffic. Just previous to swinging the movable base H is raised, and the counterweight at the end of the lever L^2 causes the gate to be closed and the derailer set to derail all

traffic, and a signal is displayed at a suitable distance from the bridge to show the position of the bridge, so as to give the trains a chance to stop before reaching the open draw. The rods, levers, and shafts are operated in conduits which are prepared to receive them. There are various other things which may be substituted for the levers and rods, such as chains, wire rope, chain-sheaves, &c. In place of levers pulleys or chain-sheaves may be used, but in this case I have shown rods. I do not wish to confine myself to rods, however, as it is plainly evident that various other forms of transmitting power may be employed. The principal feature of my invention lies in having a signal displayed a suitable distance from the bridge and to have the derailer set to derail traffic and the gates placed across the roadway, all immediately before the bridge is swung, by using some of the mechanism on the bridge—such as rail-locks, latches, and jacks, &c., which cause the gates to be closed, the derailer set, and the signal displayed, all automatically, before the bridge is swung, and to have the derailer set for clear track, the gates opened, and a signal displayed to show that the bridge is closed, all automatically, just after the bridge is closed.

Having thus described my invention, I claim as new and desire to secure by Letters Patent—

1. In a derailing-switch, a casing, a switch-point mounted therein, a rod connected to the switch-point, an arm to which the rod is connected, a shaft on which the arm is carried, an arm on the shaft, a shaft having arms, a connection pivoted to the arms of the shafts, a lifting drawbridge having a movable base provided with a lug, a weighted lever controlled by the base, and suitable connections whereby the movement of the weighted lever operates the track-switch, as and for the purpose described.

2. In a derailing-switch, a switch-point, shafts and connections for throwing the switch-point, a lifting drawbridge having a vertically-movable base, weighted levers controlled by the base and switch connections whereby the movement of the weighted lever is communicated to the switch-point.

JOHN PHILO COWING.
